US00D350767S

United States Patent [19]

Kojima et al.

[11] Patent Number: Des. 350,767

[45] Date of Patent: ** Sep. 20, 1994

[54] ELECTROSTATIC COPYING MACHINE

[75] Inventors: **Fumiyo Kojima**, Mitaka; **Akira Momose**, Narashino; **Mayumi Hamazaki**; **Tatsuhiro Terasaki**, both of Tokyo; **Takafumi Hoshimura**, Kawasaki; **Makoto Sugita**, Tokyo, all of Japan

[73] Assignee: **Ricoh Company, Ltd.**, Tokyo, Japan

[**] Term: **14 Years**

[21] Appl. No.: **900,697**

[22] Filed: **Jun. 17, 1992**

[30] Foreign Application Priority Data

Dec. 17, 1991 [JP] Japan 3-38035

[52] U.S. Cl. **D18/38**; D18/39

[58] Field of Search 354/89, 90, 297, 299; 355/200, 210, 233, 234; D18/36-40; D15/80

[57] CLAIM

The ornamental design for electrostatic copying machine, as shown and described.

DESCRIPTION

FIG. 1 is a top, front and right side perspective view of an electrostatic copying machine showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

FIG. 1

FIG. 3

FIG. 2

FIG. 4

FIG. 5

FIG. 7

FIG. 6
